US00D663943S

(12) **United States Design Patent**
Walsh et al.

(10) **Patent No.:** **US D663,943 S**
(45) **Date of Patent:** **** Jul. 24, 2012**

(54) **CHILD RESISTANT CONTAINER**

(75) Inventors: **Philip Walsh**, Bristol (GB);
Christopher Althorpe, Bristol (GB);
Tom Walker, Bristol (GB); **Paul Hayton**, Bristol (GB)

(73) Assignee: **Archimedes Development Limited**,
Nottingham (GB)

(**) Term: **14 Years**

(21) Appl. No.: **29/352,864**

(22) Filed: **Dec. 29, 2009**

(30) **Foreign Application Priority Data**

Jul. 3, 2009 (EM) 001156954-0001
Jul. 3, 2009 (EM) 001156954-0002

(57) **CLAIM**

The ornamental design for a child resistant container, as shown and described.

DESCRIPTION

FIG. 1 is a front perspective view of the child resistant container showing our new design in a closed configuration; FIG. 2 is a rear perspective view thereof; FIG. 3 is a perspective view showing the exterior surfaces thereof in an opened configuration; FIG. 4 is a side elevation view of FIG. 3; FIG. 5 is a perspective view showing the interior surfaces opposite those shown in FIG. 3; FIG. 6 is an enlarged scale bottom end view of FIGS. 3-5; and, FIG. 7 is an enlarged scale top end view of FIGS. 3-5. The broken lines in the figures are for illustrative purposes only and form no part of the claimed design.

1 Claim, 7 Drawing Sheets
